UNITED STATES PATENT OFFICE.

GEORGE P. CONANT, OF GENEVA LAKE, WISCONSIN, ASSIGNOR OF TWO-THIRDS TO ALBERT E. LYITLE, OF SAME PLACE, AND CARLOS A. COOK, OF CHICAGO, ILLINOIS.

CAR-MOVER.

SPECIFICATION forming part of Letters Patent No. 254,801, dated March 14, 1882.

Application filed December 14, 1881. (No model.)

To all whom it may concern:

Be it known that I, GEORGE P. CONANT, a citizen of the United States, residing at Geneva Lake, in the county of Walworth and State of Wisconsin, have invented a new and useful Car-Mover, of which the following is a specification.

My invention relates to car-movers for moving or starting cars on side tracks or otherwise when desired, my object by this invention being to provide a device for moving or starting cars which shall combine simplicity and cheapness of construction with a simple, easy, and effective operation; and, further, to provide a car-mover so constructed and arranged that by its use a powerful leverage may be applied to one of the wheels of a car and employed to move said car in either direction. This object I attain by the device shown in the accompanying drawings, in which—

Figure 1 is a perspective view of my improved car-mover, and Fig. 2 is a view showing the manner of applying it to the wheel of a car.

Similar letters refer to similar parts throughout the different views.

In the drawings, A represents a long lever, made preferably of wood to secure lightness, tapered off at one end to form a suitable handle, and having secured to its inner or lower end, by means of a bolt or bolts or by other suitable means, a shoe, S, provided at its point with a V-shaped notch, c.

Hinged to lever A by bolt D is an arm, B, made also of wood and provided at its outer edge with a hook, C, which may be secured thereto by a loop, a, and bolt d, in the manner shown in the drawings or in any other suitable manner.

E is a brace, bent as shown in Fig. 1, one end of which is bolted to the lever A, the other having a hole, through which passes the bolt D, the other end of said bolt being provided with a washer, b.

The arm B and hook C are so arranged with relation to the lever A and shoe S that when the said arm and lever are in line the distance from the inner face of the hook C to the point

of the shoe S is a little less than the sum of the radii of the axle-wheel and axle of the car 50 to be moved.

The operation of moving or starting a car with this device is as follows: The hook C is hooked over the axle of the car to be moved in the manner shown in Fig. 2, the wheel and 55 axle being shown in dotted outlines, the groove c in the shoe S coming over the flange of the wheel. Upon pressing down upon the outer end of the lever A the notch c in shoe S impinges tightly on the flange of the wheel just 60 below the line of the center, and the car moved by means of the leverage obtained by the length of the lever A. If it is desired to move the car in the other direction, it is only necessary to remove the notch c from the flange of the wheel, 65 and, without removing the hook C from the axle, lower the outer end of the lever A, throwing the shoe up and regrasping the flange of the wheel above the line of the center. Upon pulling up the lever A the same result will be 70 accomplished as before, moving the car in the opposite direction.

It will be seen by this device a car may be moved in either direction from either end of the car and as far as desired, the shoe S slipping around the wheel when the lever is moved in one direction and impinging the flange and moving the wheel when moved in the other. 75

Having described my invention, what I claim as new, and desire to secure by Letters Patent, is—

1. In a car-mover, the combination of the lever A, having a shoe, S, provided with V-shaped notch c, the arm B, pivoted near the end of the lever and provided with hook C and 85 loop a, and the brace E, one end of which is secured to the lever and the opposite end to the arm, substantially as shown and described.

2. In a car-mover, the combination of the hook C, loop a, and the arm B, substantially 90 as shown and described.

GEORGE P. CONANT.

In presence of—

ALBERT E. LYITLE,
PAUL A. STALEY.
